CLAIM

I claim the ornamental design for the sporting shirt, as shown and described.

DESCRIPTION

FIG. 1 is a front perspective view of a sporting shirt according to the present design;

FIG. 2 is a rear elevational view of the sporting shirt of FIG. 1;

FIG. 3 is a right side elevational view of the sporting shirt of FIG. 1; and,

FIG. 4 is a left side elevational view of the sporting shirt of FIG. 1.

The broken lines form no part of the design and are for illustrative purposes only. The top and bottom views are omitted since the top and bottom of the shirt are unornamental.
